S. F. Perry, of Rockingham, Vermont.

Letters Patent.

The schedule referred to in their Letters Patent, and making part of the same, containing a description in the words of the inventor S. F. Perry himself of his improvement in the Cooking Stove:

To all to whom these presents shall come: Be it known that J. S. F. Perry of Rockingham, in the County of Rockingham and State of Vermont have invented a new and useful improvement in the useful arts called Perry's portable furnace Stove and that the following is a full and exact description thereof reference being had to the annexed drawings: Fig. 1. is a perspective view of the machine or Stove which consists of four plates of cast iron as follows: viz: The top a is one foot ten inches long by eleven wide, with two holes through it nine inches in diameter which are covered with trions of different sizes and round plates in the centers: this plate having a groove around the edge in the under side to receive the back front and end plates.

Fig. 2. is a sectional view or end view of the stove which is eight inches wide from the angle b to c the front: and one foot high from d to e on the front, and four inches deep on the back from f to g : and five inches wide across the bottom from h to i , both ends being alike with grooves in the inside at the back and front edges to receive the back and front plates, the front plate being of sheet iron --

The bottom should be made sufficiently wide and long to receive the back front and ends in grooves around its edge and to project three fourths of an inch beyond the front plate at e .

The legs ii are inserted in to the bottom by means of projections of such form as to receive a dove tail on one end of the leg. The back is made whole with the different angles represented in the drawing from h to f and sufficiently large to fit the top bottom and ends inside of the stove, two inches and a half above the bottom a grate or plate of cast iron with holes through it is placed on projections on the ends and back on which the fuel is placed to burnit.

J is an opening or damper at each end of the stove to admit fresh air and create a draft. The stove is divided into two parts by a partition running perpendicular from the centre of the grate in front to the top plate a , and from the

front to the back. The whole is confined together by means of rods or long bolts running from top to bottom through the inside of the stove the bolts having nuts at the lower end. The flue is inserted into the back near the top of the stove for the purpose of broiling, boiling or frying the top of the stove should be made use of, having a fire in one or both of the apartments as the case may require.

For baking the common double reflecting baker is made use of, which is set against the front of the stove, and receives the necessary heat from the front plate. It is intended that the dimensions and proportions of the stove may be varied to suit the view and purpose of the constructor, and also the material of which it is made.

What I claim as my own invention and not previously known is,

- 1st. the form or construction of the inner body of the stove as above described.
- 2nd. the application of the inner in connection with the common double reflecting baker to the purpose of baking.
